UNITED STATES PATENT OFFICE.

JOHN MERRY, OF NEW YORK, N. Y., ASSIGNOR TO THE BIGELOW CARPET COMPANY, OF MASSACHUSETTS.

DESIGN FOR A RUG.

SPECIFICATION forming part of Design No. 25,933, dated August 11, 1896.

Application filed July 3, 1896. Serial No. 598,041. Term of patent 3½ years.

To all whom it may concern:

Be it known that I, JOHN MERRY, a subject of the Queen of Great Britain, residing in the city, county, and State of New York, have 5 invented a Design for a Rug or Carpet, of which the following is a specification.

This invention consists of a design for a rug or carpet; and I do hereby declare that the drawing accompanying this specification conveys to any one a clear understanding of the same and is sufficient to enable such person to use my invention.

The design is characterized by two persons mounted on a tandem bicycle, which constitutes the leading feature of the design.

The design also exhibits a rural scene, characterized by a landscape comprising earth, foliage, and sky.

What I claim, and desire to secure by Letters Patent, is—

In a design for a rug or carpet, the design substantially as shown and described.

In testimony whereof I have signed my name to this specification in the presence of two subscribing witnesses.

JOHN MERRY.
